UNITED STATES PATENT OFFICE.

JOHN SCHMITTKNECHT, OF NEW YORK, N. Y.

FIRE-ESCAPE.

SPECIFICATION forming part of Letters Patent No. 219,568, dated December 4, 1883.

Application filed February 7, 1883. (No model.)

To all whom it may concern:

Be it known that I, JOHN SCHMITTKNECHT, of the city, county, and State of New York, have invented a new and useful Improvement 5 in Fire-Escapes, of which the following is a full, clear, and exact description.

Reference is to be had to the accompanying drawings, forming a part of this specification, in which similar letters of reference indicate 10 corresponding parts in all the figures.

Figure 1 is a sectional side elevation of my improvement shown as applied to a house. Fig. 2 is a front elevation of the same, the house being shown in section through the line 15 *x x*, Fig. 1. Fig. 3 is a sectional plan view taken through the line *y y*, Fig. 2.

This invention relates to improvements in fire-escapes, having for its object to admit light to the shaft and to prevent clandestine 20 entrance thereto; and it consists in providing the top of the shaft, having the ladder-rounds, with bars or a grating, and in providing its extreme upper end with a skylight, substantially as hereinafter more fully set forth and 25 claimed.

In carrying out my invention I will first describe a form of fire-escape to which it is particularly applicable.

A represents the walls of a building. B are 30 the floors of the various stories, and C is the roof.

The fire-escape is made of wrought-iron, and 35 in the form of a rectangular shaft, D, of sufficient size to allow persons to pass up and down through it freely. To the edges of the shaft D are attached a series of rounds, E, extending from the top to the bottom of the said shaft, and placed at such a distance from the farther side of the shaft as will allow persons 40 ascending and descending to place their hands and feet upon the said rounds readily and securely. The shaft D is provided on its inner side with openings arranged above each floor B and the roof C and in the basement, and

closed by doors H. The fastenings I of the 45 doors arranged above the floors are placed on the outer side, while the fastenings I of the roof and basement doors are arranged upon the inside, the latter arrangement of the fastenings being designed to prevent the opening 50 of the doors to which they are attached by burglars or other unauthorized persons. Springs J, applied to the doors H, close the latter, should the fleeing or escaping persons leave the same open. The inmates are enabled 55 to escape from any floor by way of the basement or the roof. The shaft D is extended above the roof C, and its upper end is closed by iron bars or grating F, to prevent burglars from entering the said upper end, and thus 60 obtaining access to the interior of the building. The top of the shaft D is provided with a skylight, G, which is provided with a plate of 65 glass, G', set into the top plate thereof, as shown in Figs. 1 and 2, to give light to those using the said shaft.

In the case of new buildings the shaft D can be built into any convenient part of the wall. In the case of old buildings the shaft D can be placed against the wall, at the side of the chimney, as illustrated in Fig. 2. 70

Having thus fully described my invention, I claim as new and desire to secure by Letters Patent—

1. In a fire-escape, the combination, with 75 the top of the shaft D, of an iron grating, F, substantially as herein shown and described, whereby entrance through the top of the said shaft is prevented, as set forth.

2. In a fire-escape, the combination, with 80 the top of the shaft D, of a skylight, G, substantially as herein shown and described, whereby the interior of the said shaft is lighted, as set forth.

JOHN SCHMITTKNECHT.
